(57) **CLAIM**

The ornamental design for the apparatus for organizing cord, as shown and described.

DESCRIPTION

FIG. 1 is a perspective view of the apparatus for organizing cord;

FIG. 2 is a top view of the apparatus for organizing cord;
FIG. 3 is a front view of the apparatus for organizing cord;
FIG. 4 is a left-side view of the apparatus for organizing cord;

FIG. 5 is a right-side view of the apparatus for organizing cord;

FIG. 6 is a rear view of the apparatus for organizing cord; and,

FIG. 7 is a bottom view of the apparatus for organizing cord.

1 Claim, 2 Drawing Sheets
